UNITED STATES PATENT OFFICE.

HERBERT B. WALLING, OF SALT LAKE CITY, UTAH, ASSIGNOR TO WESTERN MINING & EXPLORATION COMPANY, A CORPORATION OF UTAH.

ORE-TREATING APPARATUS.

1,246,195.

Specification of Letters Patent. Patented Nov. 13, 1917.

Application filed January 11, 1917. Serial No. 141,848.

To all whom it may concern:

Be it known that I, HERBERT B. WALLING, a citizen of the United States, residing at Salt Lake City, in the county of Salt Lake 5 and State of Utah, have invented certain new and useful Improvements in Ore-Treating Apparatus, of which the following is a specification.

This invention relates to ore treating apparatus, and more particularly to an apparatus for treating what is commonly termed free-milling ore.

One of the main objects of the invention is to provide an apparatus which will extract the finer particles of gold from the ore mixture thus avoiding the waste of these fine particles which takes place in the ordinary form of apparatus in which the pulverized ore mixed with water is passed over an inclined plate or table. A further object is to provide an apparatus having means for causing the mixture of pulverized ore and water to travel a zigzag or undulating path so as to thoroughly agitate the same 25 and bring the finer particles of gold into intimate contact with the amalgamating plates. Further objects will appear from the detail description.

In the drawings:—

Fig. 1 is a side view of the machine with one side removed,

Fig. 2 is a section taken on line 2—2 of Fig. 1.

The body of the machine comprises the 35 front plate 1, back plate 2, and the side plates 3 and 4. The side plate 4 is removably secured between end plates 1 and 2 by tie rods 5, or in any other suitable manner.

The side plates 3 and 4 are of irregular polygonal shape, the upper edge of each plate being inclined forwardly and upwardly. A launder 6 is secured through the front plate 1 adjacent the upper end thereof. This launder is inclined downwardly and rearwardly and communicates, at its inner end, with a vertical trap or casing 7 adjacent the upper end thereof. This casing communicates through its inner side, at a plane below the inner end of launder 6, with a downwardly and rearwardly inclined plate-supporting frame 8 the lower end of which communicates with the trough 9 communicating with a vertically extending casing 10 similar to casing 7, adjacent the upper end thereof. 55 An oppositely inclined frame 11 similar to

frame 8 communicates with the interior of casing 10 at its upper end at a plane beneath the lower end of frame 8, and at its lower end with a similar vertical casing 12 adjacent the upper end thereof. A discharge trough 13 communicates with the interior of casing 12 at its inner end in a plane slightly below the lower end of plate holding frame 11.

A central vertically disposed and transversely extending partition member 14 is secured in the casing 7. This partition member extends to within a short distance of the bottom of the casing and a corrugated covering or plate 15 of sheet copper is secured about the same over transverse rounded strips 16 secured to the sides of partition member 14. A similar plate 17 is secured to the inner face of the front wall of casing 7, being secured over the strips 18. A plate 19 is secured to the inner face of the back wall of the casing over the strips 20, this plate being also of corrugated construction. The plate 17 is provided at the center of each depression with a transversely extending 80 and horizontally disposed mercury cup 21, similar cups 22 being provided in the depressions of the outer half of plate 15. The plate holding frame 8 is provided with an upper frame 23 and a lower frame 24 secured in spaced relation by the spacing blocks 25 and 26 at each end thereof. A plurality of rounded strips 27 are secured to the inner face of frame 23 transversely thereof and in spaced relation. These strips 85 serve to support a corrugated sheet copper plate 28 secured thereto. A similar plate 29 is secured to the inner face of the lower frame 24 by means of the strips 30. The two plates 28 and 29 are so relatively disposed 90 that the ribs of one plate correspond with the grooves or indentations of the other plate. The upper end of frame 8 is supported by a sheet metal stirrup 31 which is secured to the inner wall 7^a of casing 7, a suitable opening 32 being provided through this wall and communicating with the space between the two plates. The lower end of the frame is supported in a similar stirrup 33 secured on the inner end of trough 9. The 105 two stirrups 31 and 33 are set into the walls 7^a of casing 7 and the side walls of trough 9, respectively, and into the ends of the frame 8 so that their outer faces are flush with the outer faces of the casing 7, the 110

frame 8, and the trough 9. A vertical partition member 34 is secured to the inner end of the bottom 35 of trough 9, which is extended for this purpose. This member 34 extends 5 transversely of the casing and to within a short distance of the bottom of the same corresponding to the member 14 of casing 7. A plurality of spaced transversely extending rounded strips 36 are secured to each 10 face of member 34, and a corrugated sheet copper plate 37 is secured about this member to these strips. A corrugated sheet copper plate 38 is secured to the transversely extending strips 39 secured to the inner face 15 of the back wall 10^a of casing 10. A similar plate 40 is secured to the strips 41 secured to the inner face of the front wall of casing 10. The plate holding frame 11 is constructed similarly to frame 8 and is provided with the upper corrugated plate 42 20 and the lower plate 43. This frame is inclined oppositely to frame 8 and the upper end thereof is supported by a sheet metal stirrup 44 and communicates with the interior 25 of casing 10 below trough 9. The lower end of frame 11 is supported by the sheet metal stirrup 45 carried by the casing 12 and communicates with the interior of this casing adjacent the upper end thereof. 30 Casing 12 is of similar construction to casing 10 being provided with the central partition member 46, the plate 47 secured thereon, the back corrugated plate 48, and the front corrugated plate 49. A forwardly and 35 downwardly inclined discharge trough 50 extends through the front plate 1 of the frame, the inner end of this trough being supported by a sheet metal stirrup 51 secured to the front wall of casing 12 and communicating with the interior thereof. A downwardly and forwardly inclined collecting trough 52 is secured between the side plates 3 and 4 and extends the full interior width 40 of the frame being positioned beneath the casings 10 and 12. 45

In using my machine, the ore which has been pulverized by the usual stamping mill is mixed with water, this mixture being run into the launder 6. Previous to running the ore mixture into the machine, the various plates are coated with mercury or amalgam, as is usual. A certain amount of mercury is also placed in the mercury cups 21 and 22, and in the corrugations of the plates 30 and 50 43, these two plates providing, in effect, riffles. The ore mixture flows from launder 6 into casing or trap 7 downward between the corrugated plates 15 and 17, and then upward between the plates 15 and 19 into 55 the upper end of the frame 8 between plates 27 and 30. The mixture then flows between plates 27 and 30 and is discharged from trough 9 downward between the plates 37 and 38, again flowing upward between plates 37 60 and 40 into the upper end of plate holding 65

frame 11. The mixture then flows downward and forward between the plates 42 and 43 into the trap 12 and downward between plates 48 and 47, again flowing upward between plates 47 and 49, the mixture being discharged 70 through discharge trough 13. During its travel through the machine, the ore mixture is thoroughly agitated and is caused to assume a zig-zag or undulating path. This results in thoroughly agitating the ore so as 75 to bring the gold particles carried in suspension thereby into intimate contact with the mercury coated surface of the plates and with the mercury contained in the cups 21 and 22 and the grooves or hollows of plates 80 30 and 43. The particles of gold which are thus brought in contact with the mercury form an amalgam therewith, this amalgam being removed and placed in a retort and heated so as to drive off or vaporize the mercury which is then condensed for further use, in the usual manner. By causing the ore mixture to assume a continuous undulating path of travel and thus bringing the particles of gold into intimate contact with 85 the mercury coated surfaces of the plates, the very fine particles of gold which are often lost in the ordinary form of machine using the flat plates due to the mechanical action of the ore mixture in supporting and 90 transporting these fine particles, are saved. For this reason this machine is of great value in treating free-milling ores in which the gold comes in a very finely sub-divided state so that, when the ore is crushed, the 95 gold is in the form of very minute particles. 100

By removing the side plate 3 of the frame of the machine the amalgam which has been formed on the plates may be quickly and easily removed for treatment or, if desired, 105 the plates themselves may be made removable. To assist in this operation, the casing 7 is provided with a beveled slide 53 which is mounted in a transversely extending slot formed in the bottom of the casing, 110 the casings 10 and 12 being provided with similar slides 54 and 55, respectively. By means of these slides the casings may be quickly and easily drained to recover any amalgam which may collect in the same, 115 the casing 7 discharging into trough 13 and the casings 10 and 12 discharging into the trough 52. In practice, I prefer to place a certain amount of mercury in the bottom of each of the casings so as to collect the 120 gold from the mixture which passes over the bottom of the casing, this amalgam being discharged and collected in the manner described. 125

As will be noted from Fig. 1 of the drawings the plate holding frame 8 may be reversed so as to have plate 27 for the lower plate and plate 30 for the upper plate. This may be accomplished by simply raising the frame out of the stirrups 31 and 33 130

and inverting the same, at the same time interchanging the ends of the frame relatively to the position which they occupied formally. This renders it possible to provide a new plate for the lower plate, the lower plate being the one which is exposed to the greater wear, in the event of this plate becoming too greatly worn. The lower frame 11 may also be adjusted in the same manner so as to reverse the relative positions of plates 42 and 43.

There may be slight changes made in the construction and arrangement of the different parts of my invention without departing from the field and scope of the same and I intend to include all such changes, as fall within the scope of the appended claims, in this application in which a preferred form only of my invention is disclosed.

What I claim is:—

1. In ore treating machines, a frame, a casing secured in said frame adjacent the front and upper edge thereof, a central partition member secured in said casing and extending downwardly therein, corrugated plates secured to the front and back faces of said casing and about said partition member, certain of said plates being provided with transversely extending mercury cups, a similar casing secured in the frame adjacent the back thereof and below the first said casing, a downwardly and rearwardly inclined plate holding frame detachably mounted on the two casings and communicating therewith, two corrugated plates carried by said frame and mounted in spaced super-posed relation, and means for discharging the contents of said casings.
2. In ore treating machines, a frame, a casing secured in said frame adjacent the front and upper edge thereof, a central partition member secured in said casing and extending downwardly therein, corrugated plates secured to the front and back faces of said casing and about said partition member, certain of said plates being provided with transversely extending mercury cups, a similar casing secured in the frame adjacent the back thereof and below the first said casing, a downwardly and rearwardly inclined plate holding frame detachably mounted on the two said casings and communicating therewith, and two corrugated plates carried by said frame and mounted in spaced super-posed relation.
3. In ore treating machines, a frame, a casing secured in said frame adjacent the front and upper edge thereof, a central partition member secured in said casing and extending downwardly therein, corrugated plates secured to the front and back faces of said casing and about said partition member, certain of said plates being provided with transversely extending mercury cups, a similar casing secured in the frame adjacent the back thereof and below the first said casing, a downwardly and rearwardly inclined plate holding frame detachably mounted on the two casings and communicating therewith, two corrugated plates carried by said frame and mounted in spaced super-posed relation.

gated plates secured to the front and back faces of said casing and about said partition member, certain of said plates being provided with transversely extending mercury cups, a similar casing secured in the frame adjacent the back thereof and below the first said casing, a downwardly and rearwardly inclined plate holding frame detachably mounted on the two casings and communicating therewith, two corrugated plates carried by said frame and mounted in spaced super-posed relation, and means for discharging the contents of said casings.

3. In ore treating machines, a frame, a casing secured in said frame adjacent the front thereof, a casing mounted in rear of and below the first said casing, supporting stirrups secured to the two said casings adapted to removably support a plate holding frame, a plate holding frame mounted in said stirrups and communicating with both of said casings, and corrugated plates carried by said frame and mounted in superposed spaced relation.

4. In ore treating machines, a frame, a casing secured in said frame adjacent the front thereof, a casing mounted in rear of and below the first said casing, supporting stirrups secured to the two said casings adapted to removably support a plate holding frame, a plate holding frame mounted in said stirrups and communicating with both of said casings, and closure members slidably mounted in the bottom of each casing whereby the bottom of the casing may be opened so as to discharge the contents of said casing.

In testimony whereof I affix my signature in presence of two witnesses.

HERBERT B. WALLING.
